UNITED STATES PATENT OFFICE

NATHANIEL B. STONE, OF WASHINGTON, DISTRICT OF COLUMBIA

MOP HOLDER

Application filed December 9, 1931. Serial No. 579,927.

This invention relates to mop-holders and, among other objects, aims to provide a simple and effective clamping device for holding rag or cloth mops and means whereby the mop 5 may be easily applied and removed from a channel-shaped member.

Other aims and advantages of the invention will appear in the specification when considered in connection with the accompanying 10 drawing, wherein:

Fig. 1 is a side elevation of a mop head embodying the invention;

Fig. 2 is a fragmentary sectional view of the 15 mop shown in Fig. 1;

Fig. 3 is a side elevation on an enlarged scale of a clamping member for holding the 20 mop; and

Fig. 4 is a face view of a releasable locking 25 member for the mop clamp.

Referring particularly to the drawing, the preferred form of mop holder is shown as comprising a handle 10 secured in a substantially cylindrical socket 11 conveniently by means of a screw 12. The lower end of the 30 handle has an axial bore 13 within which is inserted a small tube 14 and the lower end of the cylindrical socket has a lateral flange 15 which is riveted or otherwise secured to a U-shaped or channel-shaped mop carrying 35 member 16 within which a folded cloth or rag mop 17 is adapted to be inserted and gripped.

As shown in Fig. 2, the mop element 17 is made up of a plurality of plies of cloth or fabric and is gripped in the channel member 40 16 by means of a gripping bar 18 which is conveniently cut out of sheet metal or bar iron. This bar is preferably shaped somewhat like an ideal beam having its central portion strengthened or reinforced by a bowed portion 19 and, to the center of the bar is attached or secured a pin 20 conveniently by means of welding which is adapted to be inserted through an opening 21 in the channel and into the tubular sleeve 14 in the end 45 of the handle. The hole in the back of the channel is aligned with the tube 14 to facilitate easy insertion and the pin preferably has a tapered or conical end to pierce the fabric and to guide the pin into the tube.

To lock the clamping bar in gripping rela-

tion to the mop, there is shown a releasable gripping device co-operating with the pin 20 between the back face of the channel and the lower end of the handle. In this instance, the gripping member is shown as being in the 55 form of a sheet metal disk 22 having an ear 23 projecting loosely through a small opening in the socket and also presenting an opening 24 slightly larger than the pin 20, the arrangement being such that the opening is 60 normally slightly out of line with the opening in the channel and the axis of the bore 13 in the handle. This disk is slightly smaller in diameter than the internal diameter of the socket to permit it to have limited pivotal 65 movement within the socket. On the opposite side of the disk there is shown a projection 25 extending through a slot 26 cut in the end of the socket to provide a lever to 70 release the grip on the pin. The slot 26 which extends through the end of the socket permits the disk to be assembled within the socket before the channel 16 is secured to it.

On the end of the handle there is shown a 75 helical spring 27 conveniently secured by means of a staple 28. The spring acts upon the upper face of the disk 22 to press it downwardly into canting or gripping engagement with the pin 20 by virtue of the swinging or pivotal movement of the disk (Fig. 2). The 80 construction is such that the gripping bar may be freely inserted in the holder by sliding the pin into the tube in the end of the handle. As the pin is being pushed home, it tends to force the disk upwardly thereby 85 bringing the opening 24 into axial alignment with the tube and the hole in the channel; but after the pin is pushed home or as far as it will go in the tube, the spring 27 forces the disk downwardly to grip the pin on opposite sides by canting action. Thus, the disk automatically locks the pin so that the bar cannot be released without lifting or swinging the disk upwardly to its horizontal position by means of the ear 25. The ear or projection 25 may be raised by one finger and held in releasing position until the pin and bar are pulled out.

To apply the mop element 17, which may 100 be an old piece of rag, rug or toweling, the

pointed end of the pin is inserted through the middle of the fabric and pierces its own way so that the upper straight edges of the bar 18 engage the fabric at the fold. The mop is held assembled on the bar by gripping the fabric on opposite sides against the middle of the bar so that the pin is ready to be inserted in the handle. This may be done by hand. However, the shape of the bar is such that its middle portion projects below the channel when a mop element is inserted in the channel. To tighten the grip on the mop element, the mop may be placed on the floor so that the middle portion of the bar rests on the fabric at one side and, while holding the handle upright, the user may stand upon the opposite ends of the channel, thereby employing her weight to force the pin home into the handle. When this is done the opposite ends of the bar firmly grip the fabric at both sides and the canting disk or gripping member firmly holds the pin so as to prevent any accidental disengagement. The operating ear or projection 25 projects a short distance through the slot 26 in the socket to enable it to be grasped by the fingers of the user and swung upwardly to release its grip so that the mop element may be pulled out.

From the foregoing description, it will be seen that the mop holder is very simple and easy to manipulate. There are no weak parts apt to get out of order and the automatic gripping device will not be affected by ordinary rust. The user does not require any special tool to insert or release an ordinary mop rag or mop element.

Obviously, the present invention is not restricted to the particular embodiment thereof herein shown and described except as set forth in the appended claims.

What is claimed is:

1. A mop holder of the character described comprising, in combination, a wooden handle having an axial opening in its lower end; a cylindrical socket member secured to the handle and projecting beyond its end; a channel-shaped holding member secured to the end of the socket; a mop-clamping bar adapted to be inserted in the channel member; said channel member having an opening alined with the axial opening in the handle; a smooth, pointed pin integrally connected to the clamping bar adapted to pierce the mop fabric and be inserted through said opening in the channel and into the axial opening in the handle; and a spring-urged gripping plate pivotally mounted at one end in the socket and having an opening engaging opposite sides of the pin adapted to grip and hold the pin when the gripping bar is inserted in the channel.

2. A mop holder of the class described comprising in combination, a handle having an axial bore in its lower end; a tubular sleeve inserted in said bore; a socket secured

to the handle; a channel-shaped holding element secured to the socket; a gripping bar adapted to be inserted in the channel; said channel having an opening alined with said bore; a pin secured to the middle of the clamping bar adapted to project through said opening and into said tubular sleeve; a gripping disk within the socket having an opening to receive the pin and arranged between the end of the handle and the back of the channel member; said socket having an opening at one side; a projection on said gripping disk pivotally mounted in said opening; said socket having an elongated slot extending through its lower end and arranged diametrically opposite from the pivotal opening for said disk; an operating projection on the disk projecting through said elongated slot; and a coil spring secured to the lower end of the handle acting upon the clamping disk automatically to force it into canting and gripping engagement with the pin to hold the bar in gripping engagement with a mop element in the channel.

3. In combination with a mop holder of the class described, a handle; a channel-shaped holding member; a substantially T-shaped mop clamping member adapted to be inserted in the channel-shaped member; a pivotally mounted transverse gripping plate adjacent to the ends of the handle having an opening engaging the stem of the T-shaped clamping member when the clamping member is inserted in the channel to hold a fabric mop assembled therein.

In testimony, that I claim the foregoing as my own, I have hereto affixed my signature.

NATHANIEL B. STONE.
